UNITED STATES PATENT OFFICE

JAKOB BURKHARDT, OF DETROIT, MICHIGAN, ASSIGNOR TO THIRD DIMENSION PICTURES, INC., OF NEW YORK, N. Y., A CORPORATION OF NEW YORK

SHUTTER FOR PROJECTING MACHINES

Application filed February 28, 1929. Serial No. 343,341.

The main object of this invention is to provide an improved shutter mechanism for projecting machines which has very rapid opening and closing action and which minimizes flickering.

Objects relating to details and economies of my invention will appear from the description to follow. The invention is defined and pointed out in the claims.

10 A structure which is a preferred embodiment of my invention is illustrated in the accompanying drawings, in which:

Fig. 1 is a front elevation of a projecting machine embodying the features of my invention, the parts other than the shutter being shown in conventional form.

Fig. 2 is a fragmentary elevation looking from the right of Fig. 1.

Fig. 3 is a fragmentary view in section on line 3—3 of Figs. 1 and 2.

Referring to the drawings, 1 represents a cabinet or housing of a projecting machine and 2 the lens thereof. These parts are shown in conventional form only.

25 My improved shutter mechanism comprises a supporting frame 3 carried by the spaced rods 4, the frame being adjustably mounted on these rods so that they may be moved to and from the window of the projecting machine.

The frame 3 is provided with bearings 5 and 6 for the spindles 7 and 8, these spindles being vertically disposed in parallel relation and equally spaced relative to the vertical central plane of the lens.

35 The spindles are longitudinally slotted to receive the blade-like shutters 9, these shutters being secured in position by means of the screws 10.

40 The spindles are connected by the gears 11 so that they are driven at uniform speeds and in opposite directions. The spindle 7 is provided with a beveled gear 12 at its lower end meshing with a beveled gear 13 on the shaft

45 14, this shaft being connected by the chain 15 and the sprockets 16 and 17 to the driving shaft 18 projecting from the housing and suitably connected to the film driving mechanism

50 within the housing.

The sprocket 16 is adjustable on the shaft 18.

With the parts thus arranged, the shutters are driven in synchronism and at the same speed but in opposite directions. They are arranged so that their edges overlap as they rotate, see Fig. 3, this being the closed position. The opening and closing is very rapid and it is found to minimize flickering or fluttering in the projected picture.

I have especially designed my improvements for use in the projecting machine such as is the subject matter of my application for Letters Patent, Serial No. 331,309, filed January 9, 1929. My improvements are, however, very desirable for use in other relations. I have not attempted to illustrate or describe the numerous adaptations, however, as it is believed that this disclosure will enable those skilled in the art to embody or adapt my improvements as may be desired.

Having thus described my invention, what I claim as new and desire to secure by Letters Patent, is:

1. The combination in a projecting machine, of a lens, longitudinally slotted spindles disposed in upright relation and uniformly spaced relative to the vertical central plane of the lens, coating gears on said spindles, a pair of blade-like shutters disposed in said slots in said spindles, the spindles being disposed centrally of the blades and so that edges of the blades are brought into overlapping relation as the spindles revolve, and means for driving one of said spindles.

2. The combination in a projecting machine, of a lens, spindles disposed in spaced parallel relation and on opposite sides of a plane through the center of the lens and in a plane parallel to the face of the lens, said spindles being longitudinally slotted, connecting gears on said spindles, a pair of blade-like shutters disposed in said slots, the spindles being disposed centrally of the blades and so that the edges of the blades overlap when in closed position, and means for driving one of said spindles.

3. The combination in a projecting machine, of a lens, spindles disposed in upright

- relation and uniformly spaced relative to the vertical central plane of the lens and in a plane parallel to the plane of the lens, coacting gears on said spindles, a pair of blade-like shutters mounted on said spindles so that the edges of the blades are brought into overlapping relation as the spindles revolve, and means for driving said spindles in opposite directions at the same speed.
- 10 4. The combination in a projecting machine, of a lens, shutter spindles disposed in spaced parallel relation and on opposite sides of a plane through the center of the lens and in a plane parallel to the face of the lens,
- 15 blade-like shutters mounted on said spindles so that the edges of the shutters are brought into overlapping relation as the spindles revolve, and coacting gears on said spindles whereby they are driven at uniform speeds
- 20 in opposite directions.
5. The combination in a projecting machine, of a lens, a pair of blade-like shutters mounted to rotate on parallel axes disposed in a plane parallel to the face of the lens and
- 25 so that their edges are brought into overlapping relation as they revolve, and means for driving said shutters at the same speed and in opposite directions.
6. The combination in a projecting machine, of a lens, a pair of shutters mounted to rotate on parallel axes uniformly spaced relative to a central plane of the lens and disposed in a plane parallel to the face of the lens, and the means for driving said shutters
- 35 at the same speed and in opposite directions.
7. The combination in a projecting machine, of a lens a pair of shutters mounted to rotate on spaced parallel axes disposed in a plane parallel to the face of the lens and so
- 40 that their edges are brought into overlapping relation as they are rotated, and means for synchronously driving said shutters.

In witness whereof I have hereunto set my hand.

45 JAKOB BURKHARDT.
